TWO-CYCLE PUMP AND ENGINE ASSEMBLY

Joseph R. Evans, Lincoln, Nebr.

Application October 6, 1950, Serial No. 188,795

4 Claims. (Cl. 123—70)

1

This invention appertains to improvements in a two-cycle internal combustion engine and particularly to a novel construction of the cylinders and means for forcing a charge under pressure into the cylinders.

A primary object of this invention is to provide a sleeve pump piston for charging a cylinder, thus obviating the employment of inlet valves, camshafts and other attendant components.

Another object of this invention is to provide a pumping and compressing cylinder and piston for each working cylinder wherein the charge is compressed before being introduced into the cylinder for firing, thus providing economical and efficient operation and also resulting in an increase of power.

These and ancillary objects and attendant structural features of merit are attained by this invention, the preferred embodiment of which is set forth in the following description and in the accompanying drawings, wherein:

Figure 1 is a longitudinal vertical sectional view through an engine embodying the instant invention;

Figure 2 is a transverse sectional view taken on line 2—2 of Figure 1;

Figure 3 is an exploded perspective view of the pump piston;

Figure 4 is a diagram of the timing of the working and charging pistons on the crankshaft, and,

Figure 5 is a cross sectional view taken on line 5—5 of Figure 1.

Referring now more particularly to the accompanying drawings, a crankcase 10 is illustrated, in the opposing end walls of which a crankshaft 12 is journaled, with an ignition distributor 14 being conventionally associated with one end of the crankshaft. An oil pump 16 is provided and a conduit communicates the pump with the crankcase. Longitudinally spaced walls 18 and 20 project upwardly from the crank case and define cylinder assemblies 22 with the end walls of the crankcase. Each cylinder assembly 22 consists of a working cylinder 24 and a pumping and compressing cylinder 26, which serves as a supercharger for the working cylinder. The cylinders 24 are provided with jackets 28 forming cooling chambers for air or water to cool the cylinders.

Heads 30 and 32 close off the upper ends of the working and charging cylinders, respectively. Pistons 34, having conventional compression rings, are workably disposed in the working cylinders 24 and are connected by connecting rods 36 to the cranks of the crankshaft, the rods be-

ing affixed by transverse wrist pins 38 to the pistons. Spark plugs 40 are mounted in the heads 30 of the working cylinder above the combustion chambers 42 and exhaust ports 44 are formed in the side walls of the cylinders, the ports having suitable connections 46 for communication with the exhaust manifold.

Within the upper ends of each of the charging or pumping and compressing cylinders 26, a hollow piston 48 is fixed, the piston depending from the head 32 and having its walls concentrically spaced out of engagement with the walls of the cylinder 26. The lower end of the fixed piston is closed by an end wall 50 which includes with a longitudinally extending semicircular portion 52, forming an extension and lying in adjacency to the companion firing cylinder.

A pumping and compressing piston 54 is workably housed in the lower portion of each of the charging cylinders and is formed with an open lower end 56 for the reception of a connecting rod 58 journaled on the crankshaft behind the cranks receiving the rods for the firing positions, the pistons 54 being timed on the shaft for stroking ahead of the firing pistons, as will be explained.

A top wall 60 is formed on each of the pistons 54 and is formed to mate with the end wall 52 of each of the fixed pistons 48. Thus, the wall 60 is formed with an axially projecting semicircular extension or longitudinally stepped portion 62. A semicircular (in cross section) sleeve 64 extends axially from a portion of the side wall of each of the pistons 54 and constitutes a prolongation of a portion of the side wall, the sleeve slidably fitting between the fixed pistons and the cylinder walls.

A fuel line 66 communicates with each of the charging cylinders 26 by means of an intake port 68 in the side walls of the cylinders. Air is admitted into the charging chamber 70 between the fixed and movable pistons in the charging cylinders 26 through the intake or inlet port 68 and is admixed with the fuel, the mixture being compressed by the pumping piston advancing relative to the fixed piston 48. Of course, a separate air inlet could be provided in the cylinder wall and in communication with the chamber 70.

In Figure 1, the piston 34A is illustrated in a firing position, with the piston 34B in a compression position and the piston 34C at the end of the exhaust stroke. In this relative position, it will be noted that the pumping and compressing pistons 54 are timed on the crankshaft approxi-

mately 28° ahead of the firing pistons, as the crankshaft rotates, as illustrated in Figure 4.

Thus, in operation, fuel is admitted into the charging chambers 70 through the intake ports 68 on the suction or intake stroke of the pistons 54 with air being admitted into the chambers through the same ports. The pistons 54 initiate their intake strokes, as the cylinders 24 are firing, as seen with respect to piston 34A and the companion piston 54. The air is admitted immediately upon the initiation of the downward or suction stroke and when the sleeve uncovers the intake port 68 in the side of the cylinder, and the fuel is also sucked into the chamber for admixing with the air. As seen with respect to piston 34C, the piston 54 is initiating its compression stroke, as the working piston 34C is at the end of its exhaust stroke, the sleeve closing off the fuel intake port.

The sleeve also, in the compression stroke of the pumping and compressing piston 54, closes off an opening 76 in the wall of the firing cylinders, which opening communicates the firing chamber with the compression chamber.

At the end of the compression stroke of the piston 54, the piston 34B is compressing. Slightly before that, the charge compressed by the piston 54 is transferred through the connecting passage or opening 76 into the firing chamber in the firing cylinders, the sleeve being formed at its lower end with an opening 78 for this purpose. The pistons 34 close off the openings 16, as seen in the showing of piston 34B.

Thus, the opening 76 is closed off either by the firing pistons or the sleeve except when the sleeve opening 78 aligns therewith for a transfer of the compressed charge.

An opening 74 is transversely formed in the side wall of each piston 48 and a vertical opening 72 is formed in the extended bottom wall 52, the openings being provided to relieve the heads 32 since a portion of the charge would possibly be compressed by the sleeve 64 moving in the space between the cylinder wall and piston wall. Such compression would result in blowing the heads off but with the openings provided the small compressed charge would be exhausted back into the chamber 70.

Having described the invention, what is claimed is:

1. In an internal combustion engine, a working cylinder, a piston working in said cylinder, a crankshaft, a connecting rod connecting the piston to a crank of the shaft, a charging cylinder disposed alongside the working cylinder and having fuel and air intake ports, a passage providing communication between the cylinders, a piston fixed at one end of the charging cylinder and spaced out of engagement with the walls thereof, said piston having a stepped end, a movable pumping piston working in the charging cylinder and connected to the crankshaft for reciprocation ahead of the piston in the working cylinder, a sleeve formed on the movable piston and extending axially therefrom as a prolongation of the side wall thereof, said sleeve being arranged to close off said passage and slidably engage between the wall of the charging cylinder and the fixed piston, a stepped end on the movable piston complementary to the stepped end of the fixed piston and arranged to mate therewith on the compression stroke of the movable piston for compressing fuel therebetween, and means formed in the sleeve for transferring the compressed fuel to the firing chamber

through said passage as the working piston is in its compression stroke.

2. In an internal combustion engine, a working cylinder having a head, a piston working in said cylinder, a crankshaft, a connecting rod connecting the piston to a crank of the shaft, a charging cylinder disposed alongside the working cylinder and having a fuel intake port and an air inlet, a passage providing communication between the cylinders, a piston fixed at one end of the charging cylinder and spaced out of engagement with the walls thereof, said piston having a stepped end, a movable pumping piston working in the charging cylinder and connected to the crankshaft for reciprocation ahead of the piston and the working cylinder, a sleeve formed on the movable piston and extending axially therefrom as a prolongation of the side wall thereof, said sleeve being arranged to close off said passage and slidably engage between the wall of the charging cylinder and the fixed piston, a stepped end on the movable piston complementary to the stepped end of the fixed piston and arranged to mate therewith on the compression stroke of the movable piston for compressing fuel therebetween, means formed in the sleeve for transferring the compressed fuel to the firing chamber through said passage as the working piston is in its compression stroke, an exhaust port formed in the working cylinder, and ignition means carried by the head of said working cylinder.

3. In an internal combustion engine, a working cylinder, a piston working in said cylinder, a crankshaft, a connecting rod connecting the piston to a crank of the shaft, a charging cylinder disposed alongside of the working cylinder and having a fuel and air intake port, a passage providing communication between the cylinders, a piston fixed at one end of the charging cylinder and spaced out of engagement with the walls thereof, said fixed piston having a stepped end, a movable pumping piston working in the charging cylinder and connected to the crankshaft for reciprocation ahead of the piston in the working cylinder, a sleeve formed on the movable piston and extending axially therefrom as a prolongation of the side wall thereof, said sleeve being arranged to close off said passage and slidably engage between the wall of the charging cylinder and the fixed piston, a stepped end on the movable piston complementary to the stepped end of the fixed piston and arranged to mate therewith on the compression stroke of the movable piston for compressing fuel therebetween, said sleeve having a transverse opening in the end thereof adjacent to the movable piston, the opening being registrable with said passage for transferring fuel compressed in the charging cylinder into the working cylinder.

4. In an internal combustion engine, a working cylinder having a working piston operating therein, a charging cylinder, a fixed piston in one end of said charging cylinder, said fixed piston being spaced from the side wall of said charging cylinder, a movable fuel compressing piston operating in said charging cylinder between said fixed piston and to the other end of the charging cylinder, a fuel charging port leading from said charging cylinder into said working cylinder from a point in said charging cylinder between said fixed and movable pistons, a sleeve on said movable piston positioned in the space between said fixed piston and the side wall of said charging cylinder, said working piston being arranged to close said

charging port in an inner position of said working piston and said sleeve being arranged to close said charging port in one position of said movable piston and having an opening arranged to register with said charging port to uncover said charging port in another position of said movable piston, a fuel inlet port leading into said charging cylinder at a point between the fixed and movable pistons therein, exhaust means for the working cylinder, and operating means connecting said working piston and said compressing piston for coordinated operation, said charging port and said fuel inlet port being longitudinally spaced from each other with respect to the length of the charging cylinder, said fixed and movable pistons having facing ends, and mated step extensions on said ends, the end of the fixed piston terminating at one side of the fuel inlet port and the step extension of the fixed piston terminating at the same side of the charging port, the end of the movable piston being arranged to approach the step extension of the fixed piston and partially close said charging port with the step extension of the movable piston approaching the end of the

fixed piston and closing said fuel inlet port on the compressing stroke of said movable piston whereby fuel is compressed in said charging cylinder and charged into said working cylinder through said sleeve opening and said charging port.
